BINDING DEVICE

Arthur R. Gustafson, Chicago, Ill.

Application January 12, 1942, Serial No. 426,385

9 Claims. (Cl. 281—25)

The present invention relates to binding devices of the type used in connection with loose-leaf records and files adapted to be stacked and permanently bound for storage and future reference.

It is an object of the invention to provide a novel binding device of the above mentioned general type which is simple in construction, cheap to manufacture, easy to use and effective for permanently binding record or other file pages in book form.

It is a further object of the invention to provide a new and improved device of this character which may be easily and quickly applied to bind a plurality of record pages into book form and which, when so assembled to form a permanent record book, will permit the storing of a plurality of such books in flat face-to-face relation, requiring minimum storage space.

It is a further object of the invention to provide a novel binding device which may be used in connection with stacks of pages of varying heights and which includes simple, yet effective, means for rigidly maintaining the thickness dimension of the stack.

It is a still further object of the invention to provide a device of this character including new and improved means for identifying the respective stacks of bound material and which may be employed in connection with stacks of any size.

Further objects and advantages of the invention will become apparent as the following description proceeds, taken in connection with the accompanying drawing in which:

Figure 1 is a perspective view of a binding device in association with a stack of record pages and embodying the features of the present invention.

Fig. 2 is a fragmentary perspective view similar to Fig. 1 and showing the stack of bound material in dot and dash outlines.

Fig. 3 is a fragmentary perspective view of one corner of the stack of material, illustrating certain details of construction.

Fig. 4 is a detailed perspective view similar to Fig. 3 and showing the binding device only partially assembled with respect to the stack of pages.

Fig. 5 is a perspective view of a backing member adapted for association with the bound record pages illustrated in Fig. 1.

Fig. 6 is a fragmentary, vertical, sectional view on an enlarged scale taken through the rear of the assembly of Fig. 1.

While the invention is susceptible of various

modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

- 10 As is frequently necessary in large business establishments where a great mass of loose-leaf correspondence and record pages accumulate and must be stored in the form of permanent records, means are provided for permanently binding stacks of accumulated pages of various sizes so that the records may be stored for easy reference. One of the difficulties encountered heretofore in connection with the binding and storing of such record material is that the binding means, if convenient to apply and effective to permanently and securely bind the material, has conventionally been of a type rendering the storing of the stacks inconvenient. Thus, for example, binding posts have been employed which protrude from the top and bottom of the stacks and interfere with compact storage thereof. In organizations such as railroad offices a tremendous quantity of this material accumulates, and compact storage is of utmost importance. At the same time a binding means which is easy to apply and remove, which will render the records conveniently accessible for reference purposes, and which is simple in construction and effective to permanently bind the records must be provided.
- 35 Applicant has provided by the instant construction a novel device which may be used to permanently and securely bind stacks of record material of varying sizes into neat bound volumes which are conveniently accessible for reference and which have no protruding elements to interfere with compact storage. At the same time, applicant has provided a device which is simple in construction, which may be manufactured cheaply and which is extremely simple and effective in use.

The embodiment of the present invention, selected for illustration, comprises generally a stack of pages 10 having on its respective opposite faces backing boards or covers 11 and 12 formed with weakening grooves 13 extending longitudinally of the rear edge of the stack and adjacent thereto to permit opening of the covers and provide easy accessibility to the pages contained in the bound volume.

In the present instance, a two-part binding for the stack of pages comprises two flat strips of metal 14 and 15 each having end portions 16 and 17 lying flat against the faces of the stack parallel to the bound edge thereof and an intermediate portion 18 extending edgewise into slits 19 and 20 cut in the end edges of the stack. The intermediate and end portions of each strip are integrally connected together by double bends 21 which will lie flat against the opposite faces of the stack and rigidly determine the thickness dimension of the stack. As illustrated herein, these double bends are formed by bending the end portions 16 and 17 first on a transverse line 22 at right angles to the intermediate portion 18 (Fig. 4) to extend parallel with the side edges of the stack and project rearwardly therefrom. Thereafter the ends are bent on a forty-five degree line 23 at one hundred eighty degrees to the first bent portion to lie flat against the faces of the stack parallel to the bound edge thereof. In this position, it will be seen that one side edge of the bent end portion lies substantially in the plane of the intermediate portion. Suitable means, such, for example, as crimped fasteners 24 and 25 are provided for securing the overlying ends of the strips to hold them in the side edge slits 19 and 20.

In assembling a stack of pages into a bound volume, all that is necessary is to cut the pair of complementary slits 19 and 20 in the opposite side edges of the stack adjacent the rear thereof in any suitable fashion. I have found that the slits may be desirably formed as saw kerfs. The intermediate portions 18 of the strips 14 and 15 are then inserted edgewise in the slits 19 and 20 and, depending on the thickness dimension of the stack, the right angle bends 22 are formed so that the ends 16 and 17 of the strips extend rearwardly from the stack in parallelism to the side edges thereof. (Fig. 4.) Thereafter the bends 23 on forty-five degree lines are formed in each strip adjacent the bend 22 to produce the double bend 21. This second bending operation projects the end edges of the strips flatwise along the rear edge of the stack, in which position the overlapping edges are secured by the fasteners 24 and 25.

It will be apparent that by virtue of this construction the pages may be firmly clamped and bound and any tendency of the pages to separate is resisted by the double bends 21 which are held firmly in position by tension on the intermediate portions 18 of the strips lying within the slits 19 and 20. Thus, the double bend formations serve as rigid means for determining the thickness dimensions of the stack and any tendency of the strips to bow or move outwardly under the spreading force of the pages is obviated.

I have provided a marker or identifying means which may be associated with stacks of pages of any thickness. In the present instance, this identifying means comprises a channel-shaped member 26 (Fig. 5) having an intermediate flat portion 27 adapted to lie against the rear edge of the bound volume and a pair of legs 28 and 29 extending at right angles to the intermediate portion 27 and adapted to lie between the pages of the stack. Desirably, the channel member 26 is of substantially the same length dimension as that of the bound stack and the legs 28 and 29 thereof are formed with complementary slits 30 and 31 respectively which register with the slits 19 and 20 and are adapted to receive the intermediate portions 18 of the strips 14 and 15. It will be observed that regardless of the thickness

of the stack of pages 10 the identifying means may be associated therewith by simply inserting the leg portions of the channel-shaped member between the appropriate pages of the stack prior to assembly of the binding devices 14 and 15 therewith.

It will be apparent from a consideration of the foregoing that I have provided a new and improved binding device which is extremely simple in construction and accordingly cheap to manufacture. At the same time the two-part binding device is easy to use and extremely effective for firmly securing a stack of record pages in book form. Such records may be conveniently stored in the minimum amount of space and are conveniently accessible for future reference. The pages are firmly clamped between the double bends 21 and any separating tendency is resisted by a straight tension thrust imparted to the intermediate portions of the strips lying within the slits.

I claim as my invention:

1. A two-part binding for a stack of pages comprising two flat strips each having portions adapted to lie flat against the faces of the stack parallel to the bound edge thereof, and a portion adapted to extend edgewise into a slit in one end edge of the stack and located in a plane parallel to the longitudinal edges of the first-mentioned portions, the portions being connected by a double bend rigidly determining the length of the last-mentioned portion, the ends of each strip being secured to the ends of the other strip to hold the strips in the slits.

2. A device for binding a stack of pages comprising, in combination, a pair of metal strips, each having an intermediate portion adapted to be inserted edgewise into a slit cut into the end edges of the pages, each end of each strip being bent into a plane at a right angle to the plane of said portion and extending parallel to the width of said portion to lie flatwise against the face of the stack and to extend parallel to the back edge of the stack, the bent portions providing relatively rigid means determining the length of said portion.

3. A device for binding a stack of pages comprising, in combination, a pair of metal strips, each strip having an intermediate portion adapted to be inserted edgewise into a slit cut into an end edge of the stack, each end of each strip being bent on a transverse line at right angles to said intermediate portion and then on a forty-five degree line so that one side edge of said end lies in the plane of said portion and said end of each strip lies flatwise against the face of the stack and extends parallel to the back edge of the stack, and means for securing the adjacent ends of the strips together.

4. A device for binding a stack of pages comprising a metal strip having an intermediate portion adapted to be inserted edgewise into a slit cut in an end edge of the stack, each end of said strip being bent on a transverse line at right angles to said intermediate portion and then on a forty-five degree line at one hundred eighty degrees to the first bent portion so that the end portions of said strip lie flatwise against the face of the stack and extend parallel to the back edge of the stack.

5. A device for binding a stack of pages comprising, in combination, a pair of metal strips, each having an intermediate portion adapted to be inserted edgewise into a slit cut into an end edge of the stack, each end of each strip being

bent to lie flat against a face of the stack and to extend parallel to the bound edge thereof, the bent portions of each strip including overlapping parts of the strip lying flat against the faces of the stack and rigidly maintaining the length of said intermediate portion, and means for securing the adjacent ends of the strips together.

6 A device for binding a stack of pages comprising, in combination, a pair of metal strips secured at their ends to provide a loop adapted to extend around the stack, each strip comprising an intermediate portion and two end portions, the intermediate portion being connected to each end portion by a double bend on lines respectively transverse and at forty-five degrees to the width of the strip.

7. A device of the character described comprising, in combination, a pair of metal strips secured together at their ends to provide a loop, each strip comprising an intermediate portion connected to two end portions by double bends,

each double bend being on a line substantially crosswise of the strip and a line at an angle to the width of the strip, the two lines meeting at one edge of the strip.

5 8. A device of the character described comprising, in combination, a pair of metal strips secured together at their ends to provide a loop, each strip comprising an intermediate portion and two end portions, each end portion being 10 connected to the intermediate portion by a double bend on lines at different angles to the width of the strip and meeting at one edge of the strip.

9. A device of the character described comprising, in combination, a pair of metal strips secured together at their ends to provide a loop, each strip comprising an intermediate portion and two end portions, each end portion being 15 connected to the intermediate portion by a double bend along two angularly related lines providing 20 an overlapping of the strip between said lines.

ARTHUR R. GUSTAFSON.
